UNITED STATES PATENT OFFICE.

ANDREW J. BURR, OF OLYMPIA, WASHINGTON TERRITORY.

ROLLER-DREDGE.

SPECIFICATION forming part of Letters Patent No. 273,021, dated February 27, 1883.

Application filed September 21, 1882. (No model.)

To all whom it may concern:

Be it known that I, ANDREW J. BURR, a citizen of the United States, residing at Olympia, in the county of Thurston, Washington Territory, have invented a new and useful Improvement 5 in Roller-Dredges, of which the following is a specification.

My invention relates to improvements in dredging-machines for use under water in leveling and removing ridges and bars from river and harbor beds, the same being towed by a steamboat or other suitable power to drag it on the ridge or bar to be removed, by which means the earth or whatever constitutes the 15 ridge or bar is loosened, so that the current of water may wash it away.

To this end my invention consists of a roller-dredge constructed as hereinafter fully described and set forth, reference being had to 20 the accompanying drawings, in which—

Figure 1 is a central horizontal section of my invention, part in elevation. Fig. 2 is a side elevation of the same, part in section; and Figs. 3 and 4 are detail views of different styles 25 of teeth, showing also the mode of fastening the same to the roller-disks.

A represents the shaft, upon which the disks B are firmly secured by means usual for such purposes, such as set-screws or slots and keys.

30 C C are the digging or dredging teeth, provided with long flattened shanks c, through each of which are two bolt-holes, a a', provided with bolts and nuts for securing the teeth to the disks B. To this end the disks are provided with corresponding bolt-holes, e e', situated radially relative to each other in the disk, through which holes a a' e e' bolts are passed to firmly secure the tooth-shanks to one side of the disk, the tooth proper projecting beyond the disk, as shown. The holes e' of the inner circle are elongated to allow the bolt at the end of the tooth-shank to be set along, so as to give the desired pitch to the tooth relative to the circle of the disk.

45 The ends of the shaft A are journaled in a frame, E, like an old-styled road-roller, and this frame is provided with a chain to attach the implement to a steamboat or other motive power, by which means the roller is dragged 50 over the bar which is to be removed, advancing in the plane of the disks, which revolve by contact with the earth. The shaft A may be of any suitable length, supplied with any desired number of disks, and each disk may have 55 any suitable number of teeth secured to it.

To meet different emergencies I provide two styles of teeth, one of which is spoon-shaped, as in Fig. 3, the concavity facing to the front, and the other, like a cultivator-tooth, concave at the rear, as in Fig. 4, while pointed forward. 60

The advantage of this invention over the common drag-harrow or gang-plow for loosening sand-bars, &c., in river-bottoms is, principally, that while the harrow or plow really anchors the boat to which it is tied as soon as 65 the teeth bury in the earth, this rolling dredge, as its name indicates, rolls while it digs, thus passing over the ground which it digs up without any unnecessary expenditure of power on the part of the steamboat hauling it. It also 70 carries the sand or mud in the spoons up to the top of the dredge, thus giving the current of water more opportunity to wash it away than if merely stirred on the bottom of the stream, and by the teeth or spoons being secured to the disks the water may pass between and carry away the rile, instead of forming an eddy for the rile to settle in, as a drum would do. 75

Having thus described my invention so as 80 to enable others skilled in the art to construct and operate the same, what I claim as my invention, and wish to secure by Letters Patent, is—

1. The combination, with the frame E, the 85 shaft A, journaled therein, and the disks B, secured on said shaft, of the teeth C, shaped like spoons or like cultivator-teeth, secured to said disks, as shown and described.

2. The combination, with one or more disks, 90 B, suitably mounted to form part of a dredging-machine, of the curved teeth C, provided with biperforated flattened shanks c, secured to the face of said disk by two bolts passing through both shank and disk, as shown and 95 described.

3. The disk B, suitably mounted to form part of a dredging-machine, said disk being provided with two concentric circles of holes, e e', paired radially, in combination with teeth C, 100 provided with biperforated shanks c, each hole e' of the inner circle in disk B being elongated to allow the bolt a' at the end of shank c to be set at different angles around bolt e as a center, for the purpose of giving any desired 105 pitch to the tooth, as shown and described.

ANDREW J. BURR.
